VLADIMIR K. ZWORYKIN, OF SWISSVALE, PENNSYLVANIA, ASSIGNOR TO WESTINGHOUSE ELECTRIC & MANUFACTURING COMPANY, A CORPORATION OF PENNSYLVANIA.

MERCURY-ARC DEVICE.

Application filed November 21, 1925. Serial No. 70,558.

My invention relates to mercury-arc discharge devices and it has particular relation to means for initiating an arc upon the surface of the mercury cathode used in such devices.

Of the many starting devices proposed for mercury-arc tubes, those that have found most general application have involved a movable mechanism for making contact between an auxiliary electrode and the main body of the mercury cathode and starting the arc by interrupting the contact.

The principal object of my present invention is to provide a starting device which has all the advantages of the devices utilizing mechanical motion of the electrodes, but which obtains a starting arc upon the surface of the mercury cathode without mechanical motion of either the rectifier or the electrodes.

Another object of my invention is to provide a self-restoring fuse-like mercury thread in the interior of the rectifier and to initiate the rectifier discharge by sending through the mercury thread a current sufficient to interrupt the continuity of the thread and start an arc thereon, the arc being transferred to the main surface of the mercury cathode.

A further object of my invention is the provision of means for utilizing the variation of the conditions in a column of conducting liquid to actuate an operating mechanism in response to a flow of current through said column.

According to my invention, I provide near the surface of the mercury electrode, an insulating body having a perforation communicating at one end with the body of the mercury cathode and being filled with a thread of mercury. A leading-in wire provides an electrical connection to the other end of the mercury thread in the perforation. By momentarily sending a relatively large current through the fuse-like mercury thread, the conducting connection effected by the mercury thread is blown up and an arc is started which is suitably transferred to the main surface of the mercury electrode.

The foregoing and other objects of my

invention will be best understood by reference to the accompanying drawing, wherein

Figure 1 is a diagrammatic view of a rectifier system embodying my invention,

Fig. 2 is a sectional view illustrating in detail the portion of the rectifier near the cathode, together with a starting device embodying my invention,

Fig. 3 is a view similar to Fig. 2 embodying modifications of my invention,

Fig. 4 is a sectional view along the line V—V of Fig. 3, showing the laterally projecting arm near the mercury cathode, and

Fig. 5 is a view similar to Fig. 2 illustrating a still further modification of my invention.

Referring to Fig. 1, I have shown a familiar type of two-phase rectifier comprising a glass envelope 1 provided with two anodes 3 and 4 and having a mercury cathode 5 in a depending portion 6 of the envelope. The rectifier is supplied through a transformer 7 having a secondary winding 8 having its end terminals connected across the anodes 3 and 4, the midpoint of the secondary winding 75 constituting one terminal 9 of the direct-current load (not shown). The mercury cathode 5 constitutes the other terminal of the direct-current load.

If the discharge tube is out of operation and a load is connected to the rectifier, rectification will not start unless electron emission is somehow started upon the surface of the mercury cathode.

My invention contemplates a novel means for initiating an electron discharge upon the cathode surface by producing thereon an arc without the employment of mechanical current interrupting means in the interior of the rectifier. To this end, I provide a horizontal tubular member 12 of heat-resistant insulating material, such as quartz, disposed adjacent to the surface of the mercury cathode 5 and having a perforation 13, preferably of capillary dimensions, extending throughout substantially the entire length thereof. One end 14 of the perforation is open and communicates with the main body of the mercury cathode 5, while the other end of the perforation is enlarged to provide a pocket

15 into which is sealed a leading-in wire 16 projecting through the walls of the rectifier to the exterior thereof.

The perforation 13 is so disposed under the 5 level of the mercury that the mercury fills the interior thereof in the form of a thin thread providing an electrical connection between the end of the leading-in wire 16 and the main body of the mercury cathode.

10 The tubular member 12 is provided with a lateral extension 18 opening somewhat above the edge of the mercury surface 19, the edges of the opening separating the main surface of the mercury electrode from the 15 small drop of mercury filling the space in the opening.

To start the rectifier, a current is sent through the mercury thread filling the longitudinal perforation 13 from any convenient 20 source of direct current, such, for example, as a standard rectifier circuit 20 energized by a transformer 21. A switch 22 is provided by means of which the current supplied by the rectifier 20 to the leading-in wire may be 25 turned on or off at will. Since the current-carrying capacity of the thread is very small, it is rapidly heated and blown up like a fuse, starting an arc which is expelled through the lateral opening 18 to the surface 19 of the 30 mercury cathode. For the purposes of my invention, it is not material whether the arc develops in the interior of the perforation 13 before the mercury disposed therein is expelled through the opening 18 or afterwards, the principal requirement being that 35 the arc shall be given a good opportunity to transfer to the main surface of the mercury cathode.

The tubular member 12 is provided with a 40 bend at its open end in order to increase the resistance to the motion of the mercury through the end opening 14 when a current is sent therethrough and to direct the principal force and movement of the mercury toward the lateral opening 18 projecting above 45 the surface of the mercury, as I found that the starting operation is facilitated by such arrangement.

In the preferred construction of my invention, as shown in Fig. 2, the leading-in wire 16 projecting into the pocket 15 of the tubular member 12 is tightly sealed into the quartz body of the member in order to increase the force tending to expel the mercury 50 from the perforation 13. However, I have obtained very good results with a leading-in wire 16 which is only loosely disposed in the surrounding portion of the tubular member 12, permitting communication between the 55 interior of the pocket 15 and the space above the mercury surface.

In the modification of my invention shown in Figs. 3 and 4, the depending portion 6 of the discharge tube is provided with a laterally-projecting extension 42 having a thin

groove or channel 43 in its bottom, which is disposed approximately on the level of the surface of the mercury cathode. The extreme end of the extension 42 is depressed to provide a mercury-filled pocket 45 which 70 is provided with a leading-in terminal wire 46. The discharge in the tube is initiated by sending a current through the thread of mercury filling the channel 43 of the extension 42 until the thread-like body is interrupted and an arc is formed thereon. 75

In the modification of my invention shown in Fig. 5, the depending portion 6 of the mercury tube is provided with an inwardly projecting trough having at its bottom a 80 groove or channel 52 which is substantially on the level of the mercury of the rectifier cathode. The groove or channel 52 is filled with a thread of mercury extending between the main body of the mercury cathode 53 and an insulated pocket 54 at the end of the trough 85 near the wall of the vessel, a leading-in wire 55 serving to make electrical connection with the mercury-filled pocket 54. The device in Fig. 5 operates similar to that of Fig. 3. 90

I claim as my invention:

1. The combination with a mercury-arc discharge device comprising a vessel and a mercury electrode in said vessel, of a starting means for initiating electron emission upon the surface of the mercury, comprising a member of insulating material having a tubular perforation submerged in the mercury, said perforation being in communication with the body of mercury and so disposed that it is filled with a thread of mercury, an insulated lead-in connection for said member to provide a current path through said thread, said member having a portion opening above the surface of the mercury and communicating with said thread, whereby upon sending current through said thread, mercury is expelled through said opening and an arc is started on the mercury surface. 95

2. The combination with a mercury-arc discharge device comprising a vessel and a mercury electrode in said vessel, of a starting means for initiating electron emission upon the surface of the mercury, comprising an insulating member of heat resistant insulating material partially submerged under the mercury surface, said member having a longitudinal tubular perforation having an open end communicating with the body of mercury, said perforation being closed at the opposite end and so disposed as to be normally filled with a thread-like column of mercury, an insulated lead-in connection for said column disposed near the closed end whereby a current path is provided through said column, said member having a lateral perforation extending from said column and opening above the surface of the mercury and adjacent to the same, said member being so arranged that upon sending current through 100 105 110 115 120 125

said column, mercury is expelled through said lateral opening and an arc is initiated therethrough.

3. An electrical discharge device comprising a pair of mercury electrodes electrically connected through a narrow channel containing mercury, substantially parallel to the mercury surfaces and having insulating side

and bottom walls but vented on its upper side, whereby vaporization of the mercury in said channel causes its expulsion in an upward direction. ¹⁰

In testimony whereof, I have hereunto subscribed my name this 13th day of November, 1925.

VLADIMIR K. ZWORYKIN.
